BRAKE BEAM SAFETY DEVICE

Edwin G. Busse, Chicago, Ill., assignor to Chicago Railway Equipment Company, Chicago, Ill., a corporation of Illinois

Application December 30, 1931, Serial No. 583,998

11 Claims. (Cl. 188—210)

This invention relates to railway rolling stock and consists in a novel safety guard for brake beams for use particularly in brake rigging where the brake levers are inclined from the vertical 5 and are pivoted to the brake beam and to the connecting rods in different vertical planes. In a familiar arrangement of brake rigging the bottom connection is located above the beams and passes through the truck bolster which serves as 10 a safety guard to prevent the rod from dropping to the track in case of loss of a lever pin.

If vertical brake levers were used in this type of rigging, the bolster would also serve as a safety guard for the beams, through the bottom 15 connection, in case of failure of the brake hanger. However, due to the inclination of the levers at an angle of substantially forty degrees from the vertical and due to the necessary clearance between the rod and bolster and the play 20 in the connections between rod, lever and beams, it has been found that the lever alone does not prevent the end of the beam from falling below the clearance limit in case of failure of a brake hanger.

25 Flexible links have been provided heretofore which parallel the brake lever and extend between the connecting rod and the front of the beam at the center. Such a link serves to guide the beam in its movement towards and away from the wheels, holding it against tilting and maintaining the brake shoes parallel to the wheel treads, but does not safeguard the beams as has been suggested.

The main object of the present invention is to 35 provide novel means for utilizing a brake rod for safeguarding adjacent brake beams as well as properly balancing the same. This object is attained substantially by providing a link or bracket extending from a brake rod, which is spaced vertically and horizontally from the center of the beam, to a point on the beam located in substantially the same vertical plane as the rod.

In the accompanying drawings which illustrate the invention—

45 Figure 1 is a vertical longitudinal section showing parts of a truck and brake rigging.

Figure 2 is a vertical transverse section taken on the line 2—2 of Figure 1, portions of the side frame being broken away for clearer illustration 50 and the bolster being shown in broken lines.

Figure 3 is a detail vertical transverse section taken substantially on the line 3—3 of Figure 1.

55 Figure 4 is a detail section corresponding to Figure 1 and showing a modified form of safety guard.

Figure 5 is an end view of the safety guard.

Figure 6 is a view corresponding with Figure 5 but showing another modification of the guard.

Figure 7 is a side view of still another form of safety guard.

Figure 8 is an end view of the guard shown in Figure 7.

Figure 9 is a vertical transverse section through a spring plank type of truck and showing the safety guard applied to brake rigging of a different type.

Figure 10 is a detail vertical section taken on line 10—10 of Figure 9.

In Figures 1, 2 and 3, brake rigging is illustrated comprising truss-type brake beams including compression members 1, tension members 2, struts 3, and brake levers 4 and 5 pivoted at their lower ends to the struts. Lever 4 is anchored to a bracket 5 projecting from bolster 6. A brake lever connection 7 has jaws 8 at each end pinned to the intermediate portions of levers 4 and 5 and passes through openings 9 in the bolster. Levers 4 and 5 are disposed at an angle of substantially forty degrees to the vertical, as indicated in Figure 2.

A guard member 10 has lips 10a and 10c at the top slidably engaging rod 7 and has a bracket 10b at the bottom engaging a point on compression member 1 of the left hand beam (Figure 1) at a point located vertically below the rod. Member 10 serves to prevent the brake heads 11 from dropping to the track in case of damage to or disconnection of one of the hangers 12, and also serves to support the rear end of the beam and to guide the same in its movement towards and away from the wheels.

At 13 in Figure 1 is shown a guide member which has seat-forming bosses 14 on the upper surface engaging the lower surface of rod 7. The link does not loop over the rod 7 and accordingly serves only to hold down the back of the brake beam and to guide the same in its movement towards the wheels. Member 13, as well as the member 10 previously described, is preferably, but not necessarily, made of flexible material.

In Figures 4 and 5, guard member 15 has a pair of loops 16 passing over the rod 17 and portions 18 extending beneath and engaging points on the compression member 19 located substantially vertically beneath rod 17. The member 15 is secured in place on the beam compression member 19 by crimped portions 20.

In Figure 6 the guard member 21 is similar to that shown in Figures 4 and 5 but includes intermediate portions 22 which are bent together whereby the bracket completely encircles brake

lever connection 23. Bracket 21 thus serves to limit vertical movement of the compression member 24. Obviously, the extent of this movement depends upon the size of the loop surrounding 5 the rod and the member may be shaped to slidably or pivotally engage the rod, if desired.

In Figures 7 and 8, another form of safety guard 25 includes a curved upper portion 26 pinned between the jaws 27 of rod 28 in front of lever 29. 10 The guard extends vertically downwardly from portion 26 and has an arm 30 which underlies both the compression and tension members of the beam 31 and 32. Arm 30 parallels the beam and is located substantially vertically beneath 15 the rod 28.

The particular type of brake rigging heretofore illustrated is not essential to the broadest phase of the present invention and the novel vertical safety guard might be advantageously 20 used with other types of trucks and rigging as shown, for instance, in Figures 9 and 10 where the brake beam strut or fulcrum arm 33 engages the brake lever 34 at the middle instead of at the bottom. In this case any of the forms of the 25 safety guard might be associated with an adjacent overhead rod 35 or bottom lever connection 37, but I have illustrated flexible members 36 and 38 similar to member 10 in Figures 1 to 3. Member 36 depends from rod 35 which passes over the bolster (not shown) and engages the compression member of beam 40 at a point located vertically below the rod. Member 38 depends vertically from the beam and is supported on rod 37 passing beneath the bolster. In the 30 former case, the bolster would safeguard the overhead connection and in the latter case, an additional element 39 would preferably be provided for safeguarding the bottom rod from the spring plank 41 or other truck part. It will be understood that only one of the members 36 and 40 38 is necessary to safeguard the beam and preferably only one of the members will be used in practice, instead of both, as shown.

These and other details of the invention might be varied without departing from the spirit thereof and the exclusive use of all such modifications as come within the scope of the appended claims is contemplated.

What is claimed is:

1. In combination in railway brake rigging, a 50 brake lever, a brake beam and a brake lever connection pivoted to an end and the middle portion, respectively, of said lever, and a brake beam guard, guide or support member operatively associated with said connection and a part of said beam spaced substantially vertically from said connection.

2. In combination in railway brake rigging, a 55 brake lever, a brake beam and a brake lever connection pivoted to an end and the middle portion, respectively, of said lever, and a brake beam safety guard including a portion looped over and movable along said connection and a portion underlying a point on said beam located vertically below said rod.

3. In combination in railway brake rigging, a 60 brake lever, a brake beam and a brake lever connection pivoted to an end and the middle portion, respectively, of said lever, and a brake beam safety guard including a portion secured to a 65 part of said beam spaced substantially vertically

from said connection and a portion adjacent said connection but normally spaced therefrom and arranged to engage said connection when said beam is dropped.

4. In combination in railway brake rigging, a 5 truss-type brake beam including a central pivot for a brake lever, a brake rod displaced vertically and horizontally from said pivot, and a brake beam safety guard including a portion secured to said rod and other portions underlying points on both the tension and compression members of said beam spaced substantially vertically from said rod.

5. In combination in railway brake rigging, a 10 brake lever, a brake rod and a brake beam pivoted to the middle and end portions, respectively, of said lever, and a brake beam safety guard including a part secured to the outer end of said rod in front of said lever and another part underlying a portion of said beam located substantially vertically beneath said rod.

6. In combination in railway brake rigging, a 15 brake lever disposed at an angle to the vertical, a brake rod and a truss-type brake beam pivoted to the middle and end portions, respectively, of said lever, and a brake beam guard, guide or support including a portion secured to the outer end of said rod in front of said lever and another portion underlying points on the front and back portions of the beam located substantially vertically beneath said rod.

7. In combination in railway brake rigging, a 20 brake lever, brake beam and brake rod members pivoted to longitudinally spaced points on said lever, and a brake beam safety guard secured to one of said members and having a part adjacent to but spaced from the other of said members, said part being adapted to engage said second-mentioned member only in case of lowering of a 25 beam hanging.

8. In combination in railway brake rigging, a 30 brake lever, a brake beam and a brake rod pivoted to longitudinally spaced points on said lever, and a brake beam safety guard secured to said beam and having a part passing over said rod 35 but spaced therefrom.

9. In combination in railway brake rigging, a 40 brake lever, a truss-type brake beam connected thereto, a brake rod extending above the level of said beam, and a brake beam safety guard comprising an inverted T-shaped element with its leg depending from said rod between the compression and tension members of said beam and with its cross beam underlying said members.

10. In combination in railway brake rigging, a 45 brake lever, a brake beam member and a brake rod member pivoted to end and intermediate portions, respectively, of said lever, and a guard, guide or support device for said beam including substantially vertically aligned parts one of which is secured to one of said members and the other of which is operatively associated with the other of said members.

11. In combination in railway brake rigging, a 50 brake lever, a brake beam and a brake rod connected to said lever, and a brake beam safety guard member operatively associated with said rod and with a point on the rear part of said beam substantially in vertical alignment with said rod.

EDWIN G. BUSSE.
